United States Patent Office

Des. 186,849
Patented Dec. 15, 1959

186,849

COMBINED PLANTER AND STAND THEREFOR

Winford L. Enghauser, Cincinnati, Ohio

Application May 23, 1958, Serial No. 51,059

Term of patent 3½ years

(Cl. D35—3)

Fig. 1

Fig. 3

Fig. 1 is a top plan view of the combined planter and stand therefor showing my new design;

Fig. 2 is a side elevational view thereof; and

Fig. 3 is an end elevational view thereof.

I claim:

The ornamental design for a combined planter and stand therefor, substantially as shown.
